RADIATOR COVER

Curtis H. Bevington, Chicago, Ill., assignor to The
Vulcan Radiator Company, Hartford, Conn., a
corporation of Connecticut

Application June 22, 1948, Serial No. 147,112

Term of patent 3½ years

(Cl. D81—21)

To all whom it may concern:

Be it known that I, Curtis H. Bevington, a citizen of the United States, residing at Chicago, in the county of Cook and State of Illinois, have invented a new, original, and ornamental Design for a Radiator Cover, of which the following is a specification, reference being had to the accompanying drawing, forming part thereof.

Fig. 1 is a sectional view taken on line 1—1 of Fig. 2.

Fig. 2 is a front elevation; and

Fig. 3 is a perspective view of a radiator cover embodying my new design.

I claim:

The ornamental design for a radiator cover, substantially as shown.

CURTIS H. BEVINGTON.
